FLUID ACTUATED VISE

John T. Obecny, Inglewood, Calif.

Application May 8, 1941, Serial No. 392,446

9 Claims. (Cl. 90—59)

This invention relates to an improved machine tool and more particularly to a vise for holding work and in which the jaw or jaws are operated by fluid under pressure. The primary object of the invention is to provide a vise which will hold objects of different shapes and sizes securely and effectively under continuous heavy pressure so as to avoid slipping and to apply or release the holding jaws quickly and with a minimum amount of hand labor. Another object is the production of a device of its kind which is simple, strong, durable and efficient in construction. Another object is ready adaptability of the construction for use as a hand operable tool or in connection with machines of various kinds such as are used for planing, milling, shaping, etc. A further object is to provide means for transmitting the clamping force or forces to the movable jaw or jaws at such angle as to automatically prevent the jaw or jaws from canting or shifting angularly with respect to the normal clamping surfaces of the jaws.

A preferred embodiment of my improved fluid actuated vise is illustrated in the accompanying drawings forming part of this specification. In the drawings, Fig. 1 is a side elevation of my improved fluid actuated vise showing one stationary and one movable jaw and my improvement applied thereto; said movable jaw being shown in closed clamping position; Fig. 2 is a plan of the structure shown in Fig. 1; Fig. 3 is a typical longitudinal section on a slightly increased scale of the telescopic sections of the ram and of the operating mechanism used with the structure shown in Figs. 1 and 2, parts thereof being schematic for the purpose of illustrating the operating functions; Fig. 4 is a vertical central section of a detail showing the hand controlled check valve H, used in the return duct of the compressor; Fig. 5 is a vertical central section of the by-pass check valve I; Fig. 6 is a vertical central section of the check valve M, which is interposed in the duct between the compression chamber of the compressor and the return fluid reservoir adjacent to said compression chamber, and Fig. 7 is a side elevation, partly schematic of a fluid actuated vise constructed in accordance with my invention when supplied with two movable jaws.

Referring to the drawings, A indicates a base which may be of any suitable construction to facilitate fastening on a work bench or clamping upon the bed of a machine tool. The base is shown secured to a bed element B by bolts 10, to facilitate mounting, but the use of this feature is entirely optional. Adjacent to one end of

5 the bed is an upstanding stationary jaw C, having the usual inner vertical transverse clamping face 11. The base A extends rearwardly from the jaw in a horizontal plane and is provided with a pair of parallel longitudinal gib engaging slots 12 for holding and guiding the movable jaw D. The movable jaw has a companion inner vertical transverse clamping jaw 13 which is adapted to cooperate with the stationary face 11 for engaging and holding work pieces of any 10 desired shape and size. The lower surface of the movable jaw has a pair of longitudinal gibs 14 of usual construction extending downwardly into and sliding in the slots 12 for guiding and slidably holding the movable jaw on the bed without canting or binding in a horizontal plane with respect to the normal clamping surfaces of the movable jaw. The movable jaw is actuated, that 15 is slid forwardly and rearwardly on the bed to 20 and from the stationary jaw by a fluid actuated telescopic ram E.

The ram E is composed of a plurality of telescopic hollow cylinders 15, 16 and 17, the forward member 15 of which resembles a piston rod and is formed with a head 18 which is secured rigidly to a horizontal rocker shaft 19 by the set bolt 20 or other suitable means. This shaft extends transversely through and is journaled freely in the body of the movable jaw D and the head is held freely rotatable in the rearwardly extending passageway 21 in the body of the movable jaw. The rearward end of the telescopic hollow cylindrical section 17 resembles a head piece 22 which likewise is mounted upon a horizontal transverse rotatable shaft 23 and secured thereto by the set bolt 24. This shaft is journaled in a back stop 25 which is integral with and extends upwardly from base A. The longitudinal axis of ram E, that is of the hollow cylindrical telescopic sections thereof inclines downwardly in a forward direction from the pivot coupling 23 to the pivot coupling 19 so that when the ram operates under the pressure of fluid to urge the movable jaw into forward clamping position, the force thus exerted is the resultant of longitudinal and downward stresses which tends not only to urge the movable jaw forwardly but also urges the movable jaw downwardly upon the bed to overcome tendency of the movable jaw canting in a vertical longitudinal plane as related to the normal faces of the jaws. This movement feature is important because it assists in maintaining the jaws of the vise more effectively in free normal operative position unaffected by undesirable strains.

The inner end of the ram section 15 is formed with a piston 26 of suitable construction which closes the inner end of the section and is of suitable diameter to produce a working fit in cylindrical section 16 and ported at 27 to provide a fluid compression space between sections 15 and 16, so that fluid acting under pressure admitted from section 15 tends to collapse the two sections together during the opening movement of the movable jaw D. Also the inner end of the cylinder section 16 is provided with a piston 28 of suitable construction and diameter and is ported at 29 to also provide a working space 29' for the admission of fluid under pressure from section 16 thereinto for causing the sections 16 and 17 to telescope together. The piston 28 is ported at 30 to form internal communication between sections 16 and 17. The piston 26 is adapted to overlap port 29 at or near the inner end of the stroke of the telescopic section 15 and close port 30 so that communication is established between the operating chamber within section 15 and chamber 29' between sections 16 and 17. Suitable flexible ducts 31 and 32 leading to a pair of opposite ports 33 and 34 in the casing of the three way operating valve F (shown schematically in Fig. 3) are connected with the extreme opposite ends of the operating chambers in sections 15 and 17 for directing the operating fluid, such as air under pressure, liquid, gas or any other suitable medium, in either direction desired through the ram, to urge the movable jaw into clamping and released positions.

A suitable fluid operating source is provided, the drawings showing a hand operable compressor G mounted upon the back stop 25, such as by bolts 25' in which the piston 35 is reciprocated in a fluid compression cylinder 36 by the hand operable lever 37. The cylinder 36 is surrounded by a fluid receiving return or expansion chamber 38 from which fluid to be compressed is received into the cylinder 36 below the piston through the check valve M (see Figs. 3 and 6). The compression chamber below the piston is connected with the pressure fluid inlet port 40 in the casing of the three way valve F by duct 41. The opposite return port 42 in the valve casing is connected with the return chamber 38 of the compressor by duct 43, a hand operated release automatic check valve H (see Figs. 3 and 4) being interposed in said duct. This check valve has a spring pressed check valve body 45, valve stem 46 and spring 47, which latter functions to permit opening of valve at a predetermined pressure and allows return flow of spent fluid into the return chamber G. This valve is provided with a freely reciprocable connection 48 between the valve stem 46 and a threaded, hand operated shaft 49, which latter is arranged so that by unscrewing sufficiently the valve body is positively held unseated when desired to allow free return of spent fluid through the three way valve from the exhaust end of the ram.

A suitable by-pass 50 is provided between the live outlet duct 41 from the compressor and the return chamber 38, which contains a check valve I (see Fig. 5). This check valve is controlled in operation by the interchangeable spring 51, which is of predetermined strength, whereby any excess pressure exerted by the clamping jaws over and above a predetermined amount causes the release of fluid under continued pumping action to return to chamber 38. In this manner the fluid pressure exerted by the clamping jaws is controlled automatically. A connection 52 with 75

duct 43 leading into the expansion chamber 38 of the pump or compressor is provided for the exhaust of fluid from chamber 29' during the portion of the return or releasing stroke of the ram in advance of piston 26 passing port 29. This connection is controlled by the hand operated valve 53, but can be made automatic within the spirit of the invention.

Operation

10 The three way valve has a rotatable valve body 54 which provides port passages between the ingress and egress ports in the valve casing so that in the broken line position shown in Fig. 3, the fluid compressed by reciprocation of the piston 35 passes through duct 32 into the outer telescopic ram section 17 and urges the ram sections and the movable jaw into the full line positions shown in Figs. 1 to 3 inclusive, the exhaust of spent fluid below the pistons being conducted by duct 31 through valve F into the receiving chamber 38 by duct 43, and the valve H checking return flow. During this operation the valve 53 is kept closed. When excess pressure over a predetermined amount is reached by continued reciprocation of the compressor piston, the pressure release valve I allows the excess fluid to by-pass back into chamber 38. Thus predetermined pressure is established against the movable jaw. The adjustable valve H is set to automatically check return flow of pressure fluid at predetermined pressure. When it is desired to release the movable jaw the three way valve F is reversed into the full line position shown in Fig. 3 whereupon the operation of the compressor causes pressure fluid to traverse duct 31 and urge the forward section 15 of the ram and the movable jaw backwardly. Upon section 15 approaching fully collapsed position with its piston 26 beyond port 29, continued reciprocation of the compressor piston causes pressure fluid to enter chamber 29' between sections 16 and 17 through ports 29 and urge section 16 backwardly into collapsed position with the movable jaw spaced from the fixed jaw. The spent fluid exhausts back into chamber 38 through duct 32, valve F and check H. In the same manner as before stated the by-pass functions to limit the pressure exerted by the pressure fluid during the opening operation of the movable jaw. During this return stroke fluid ahead of piston 26 in chamber 16 enters chamber 29' and is released by opening valve 53 until piston 26 passes ports 29, whereupon the fluid from chamber 15 enters chamber 29' and urges piston 28 into fully re-ceded position.

60 In the alternative construction shown in Fig. 7, both jaws J—J' of the vise reciprocate on the bed 60 and each jaw is actuated by a telescopic ram such as K or K', all of substantially similar construction as above described. A single hand operable fluid compressor and valve controlling mechanism is also employed excepting that both of the flexible ducts 61 leading to the outermost ends of the rams are connected into duct 32 and both of the flexible ducts 62 leading to the innermost ends of the rams are connected into duct 31, whereby both rams are operated simultaneously to either close or open the jaws. The hand controlled valved passageways 66 similar to passageways 52 are also provided for the release of fluid from the intermediate sections of rams K—K' previous to the period when the ports entering the chambers similar to 29' are placed in communication with the forward sections of the

rams. A feature included in Fig. 7 and not employed in the structure above described relating to Figs. 1 to 6 inclusive is an equalizing connection L, by which both jaws are positively actuated in unison. This feature consists of an idle pinion 63 journaled in fixed position between the jaws and a pair of racks 64 and 65 in mesh with the teeth on opposite sides of the pinion, one rack being attached to jaw J and the other rack to jaw J', and both racks sliding longitudinally with the closing and opening movements of the jaws. In this manner both jaws are positively actuated in unison irrespective of uneven force applied to impel them forwardly or backwardly. The axes of the two rams incline downwardly in a vertical plane as in the structure employing only one ram, both jaws being urged downwardly as well as longitudinally as above described to prevent canting.

The structures shown are only illustrative of the invention and it is to be understood that changes and modifications are contemplated within the spirit of the invention and within the scope of the following claims.

I claim:

1. In a machine tool, a bed, a pair of companion jaws on said bed, one of said jaws being slidable longitudinally, a fluid actuated ram having telescopic cylinder and cooperating piston elements arranged on an inclined longitudinal axis, the lower end of said ram being pivotally attached to said movable jaw and the upper end being movably connected to said bed and fluid actuating means connected with said ram by which the ram is actuated to urge the movable jaw longitudinally toward said companion jaw and tending to urge the movable jaw downwardly tightly compressed against the bed to prevent canting.

2. In a machine tool, a bed, a pair of companion jaw members on said bed, one of said jaws being slidable longitudinally on the bed, a fluid actuated ram having telescopic cylinder and cooperating piston elements arranged on an inclined longitudinal axis, the lower end of said ram being pivotally connected to said slidable jaw and the upper end being movably connected to said bed, fluid actuating means connected with said ram having valve controlled means by which the actuating fluid is reversible, whereby in one position of the valve means the ram is actuated to urge the movable jaw longitudinally toward said companion jaw and tightly compressed against the bed and in another position the ram is reversed to slide the movable jaw into open position.

3. In a machine tool, a bed, a pair of companion jaw members on said bed, one of said jaws being slidable longitudinally and actuating means extending longitudinally on an inclined axis downwardly towards said bed, the lower end of the actuating means being pivotally connected to said slidable jaw and the upper end being movably connected to said bed, whereby the actuating means is adapted to urge the movable jaw longitudinally towards the stationary jaw and downwardly tightly against the bed.

4. A machine tool, comprising, a bed, a stationary jaw on said bed, a cooperating movable jaw slidable upon said bed towards the station-

ary jaw, a fluid actuated power unit on the bed and pivoted to the movable jaw to reciprocate the latter toward and away from the stationary jaw, a fluid compressor connected with the power unit for actuating the latter and check valve means connected with said compressor for releasing excessive pressure of the actuating fluid from the power unit.

5. A machine tool, comprising, a bed, a jaw on said bed, a second jaw opposing the first jaw and slidable longitudinally upon said bed, a ram carried by the bed and having a movable member pivoted to said second jaw, means whereby compressed fluid may be injected into the ram for actuating said movable member in a direction for advancing the movable jaw towards the first named jaw, valve means for reversing the flow of compressed fluid through said ram for actuating said movable member in a direction for withdrawing the movable jaw from the first jaw, and a valved duct connected with the compressed fluid injecting means whereby excessive predetermined pressure is released from traversing said ram.

6. A machine tool, comprising, a pair of movable jaws slidable toward and away from each other on said bed, a companion telescopic ram for each of said jaws, each ram having a movable member pivoted to a jaw and a stationary member pivoted to said bed, the axis of each of said rams being inclined downwardly towards the bed and the jaw whereby the jaws are urged downwardly against the bed when the movable members are thrust forwardly, a fluid compressor connected with both of said rams adapted to circulate compressed fluid through said rams for actuating said movable members simultaneously in a direction for advancing the movable jaws together and valved means for reversing the circulation of said compressed fluid through said rams to actuate the movable members in a direction for simultaneously retracting the jaws apart.

7. In an assemblage as defined in claim 6, equalizing means connected with said jaws for causing them to move in unison.

8. In a machine tool, a bed, a pair of companion jaw members above said bed, one of said jaw members being slidable longitudinally on the bed into close cooperation with the companion jaw, and means pivotally connected at one end to the movable jaw and pivotally supported at its opposite end above the bed for urging said jaw into closed position and tightly against the bed by the resultant of two longitudinal and downward cooperative forces.

9. A vise including cooperating fixed and movable jaws, a bed upon which said jaws are mounted, a fluid actuated ram having a telescopic cylinder element pivoted at one end to said jaw for actuating the latter to approach the fixed jaw by the extension of the telescopic cylinder element and pivotally supported near its opposite end above the bed, and valve means for reversing the direction of flow of the actuating fluid through said ram whereby the movable jaw is opened away from the fixed jaw by the extension of the cylinder.

JOHN T. OBECNY.
